(57) **CLAIM**

The ornamental design for a knee support, as shown and described.

DESCRIPTION

FIG. 1 is a top, front, right-side perspective view of a knee support;

FIG. 2 is a bottom, back, left-side perspective view thereof;
FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines on the exterior surface of the knee support in FIGS. 1-6 and 8 depict stitching on the knee support that forms part of the claimed design.

The dashed broken line on the interior surface of the knee support in FIGS. 1 and 7 depict stitching on the knee support that forms no part of the claimed design. The dot-dashed broken lines depict boundaries of the claimed design and form no part of the claimed design.

1 Claim, 8 Drawing Sheets
